RELOADING PRESSES FOR AMMUNITION

John T. Twidwell, Pasco, Wash.

Application December 27, 1955, Serial No. 555,408

2 Claims. (Cl. 86—36)

This invention relates to reloading mechanism for ammunition, and more particularly to reloading devices adapted for the reloading of spent rifle or pistol casing shells of the center fire variety.

One of the objects of this invention is to provide in a reloading device for cartridges, means for inserting a new primer cap into a cartridge casing from which a used primer cap has been removed, there being associated therewith a magazine adapted to contain a plurality of new primer caps and there also being means to transfer the primer cap from the magazine, one at a time, into a position in alignment with the primer cap aperture in the cartridge casing or shell for subsequent insertion therinto.

Another object of this invention is to provide a reloading device incorporating means for removing a spent primer cap from a cartridge casing and means for inserting a new primer cap into the casing, there being common operating means for both mechanisms.

A further object of this invention is to provide an improved reloading device for ammunition which includes means for holding a spent cartridge casing, reload plunger means movable toward and away from the casing for the purpose of inserting a new primer cap therein, a magazine adapted to contain a plurality of new primer caps, and transfer means for transporting a single primer cap from the magazine to a position between the reload plunger and the casing so that subsequent operation of the reload plunger will effect the insertion of a new primer cap into the cartridge casing.

Still another object of this invention is to provide an improved reloading device in conformity with the foregoing object and the reload plunger, while in its position most remote from the cartridge casing, is in the path of movement of a portion of the transfer means so that when the transfer means move to a positioning aligning a new primer cap with the primer cap aperture in the shell casing, the same will be exposed for operation thereupon by the plunger means.

A still further object of this invention is to provide an improved type of reloading mechanism incorporating means associated with a common manual operating mechanism for first resizing the neck of a spent cartridge casing or shell while simultaneously removing the spent primer cap therefrom and then inserting a new primer cap into the cartridge casing.

Another object of this invention is to provide an improved reloading mechanism for ammunition wherein the neck of the shell is resized and prepared for the insertion of a new bullet, the old primer removed and a new primer inserted without necessitating the removal or repositioning of the shell being loaded.

Still another object of this invention resides in the simplicity of design, rigidity of construction and economy of manufacture.

The novel features that are considered characteristic of the invention are set forth with particularity in the appended claims. The invention itself, however, both as

to its organization and its method of operation, together with additional objects and advantages thereof, will best be understood from the following description of specific embodiments when read in connection with the accompanying drawings, wherein like reference characters indicate like parts throughout the several figures and in which:

Fig. 1 is a front elevational view of the improved reloading mechanism showing a shell or cartridge casing in place and with parts of the mechanism being broken away to show details of internal construction;

Fig. 2 is a side elevational view of the assembly as shown in Fig. 1, parts thereof being broken away to show details of construction;

Fig. 3 is an enlarged vertical section taken along the plane of section line 3—3 of Fig. 1, but showing the device operating upon the spent cartridge casing to simultaneously resize the neck thereof and remove the old primer cap;

Fig. 4 is an enlarged horizontal section taken substantially along the plane of section line 4—4 of Fig. 2;

Fig. 5 is an enlarged horizontal section taken substantially along the plane of section line 5—5 of Fig. 1;

Fig. 6 is an enlarged vertical section taken substantially along the plane of section line 6—6 of Fig. 1;

Fig. 7 is an enlarged horizontal section taken substantially along the plane of section line 7—7 of Fig. 1;

Fig. 8 is an enlarged vertical section taken substantially along the plane of section line 8—8 of Fig. 2;

Fig. 9 is a view similar to Fig. 1 but showing a modified form of construction;

Fig. 10 is a view similar to Fig. 6 but showing the modification illustrated in Fig. 9;

Fig. 11 is an enlarged vertical section showing the device when used for reinserting a bullet into the neck of the cartridge;

Fig. 12 is a vertical section taken through a device constructed for the purpose of removing bullets from a shell casing, and

Fig. 13 is an enlarged vertical section taken substantially along the plane of section line 13—13 of Fig. 1 but showing the parts in position just prior to the insertion of a new primer cap within the spent cartridge casing.

Referring now to Figs. 1 and 2, the assembly will be seen to consist essentially of a frame F constructed in any desired manner but as particularly shown, including a pair of spaced, parallel, upright members 1 and 2 interconnected along corresponding edges by a transverse web member 3 and a base 4, an upper portion of web member 3 being provided with a slot 3' for the purpose of permitting operating linkage, hereinafter described, to clear such web. As will be seen most clearly in Figs. 1 and 4, portions of the members 1 and 2 project forwardly of the web 3 and are provided therein with guideways 12, as shown, for the purpose of guidably receiving the carriage member 9 and more particularly the opposite side edge portions of carriage base 10. The carriage base 10 may be provided along one side thereof with a pair of depressions 70 and 71 cooperable with the detent plunger 69 which is normally urged by spring member 69' into engagement with the side edge portion of the carriage, the spring 69' being firmly anchored to the frame by any suitable means.

The carriage member includes a horizontally projecting ear portion 11 which, as will be seen more clearly in Fig. 3, is provided with a threaded vertical bore therethrough. This bore is adapted to receive the die member D. This die member is threaded as indicated by reference character 57 for engagement through the vertical threaded bore of the ear 11 and a stop collar 58 is also threadedly engaged on this portion 57 and retained in position thereon by the set screw 58' for a purpose which will be hereinafter described. The die is also pro-

vided with a longitudinally extending bore which extends completely therethrough and which incorporates an upper internally threaded portion *a*, a lower bore portion *b* opening onto the lower end of the die and an intermediate bore portion *62* of lesser diameter than the bore portion *b* and merging therewith in the frusto conical portion *c*.

With reference now to Fig. 3, it will be seen that the bore portion *b* is adapted to receive the portion *63* of the shell casing *S* and snugly fit therewith, whereas the internal diameter of the bore portion *62* is so chosen as to neck-down or constrict the neck *66* of the shell casing *S*, which neck will normally have been expanded to a greater or lesser degree at the time the casing was fired. The bore portion *c*, of course, provides an entrance mouth into the portion *62* during the constricting or necking-down process.

Fixed to the frame assembly *F* below the carriage *9*, is a bracket assembly *B*. This bracket includes a horizontally, forwardly projecting table portion *6*, and a depending leg *6'* which is rigidly secured to the web *3* by means of suitable fasteners such as the bolts *5*. The flange *6'* carries a forwardly projecting guide portion *7* disposed in spaced relation below the undersurface of the table portion *6*. The table portion *6* is provided therethrough with a vertical hole or opening *h* and a counter bore *h'* on the upper surface to receive the shell retaining member *32* therein, the latter being held in place by set screw *33*. The retaining member *32* includes an upraised semicircular lip *34* which is adapted to engage in the annular groove, defined by the ejector rim *35*, in the base or back portion of the shell or cartridge casing *S* and serves to hold the same in place as indicated most clearly in Fig. 3. The retaining member is also provided with a vertical bore *32'* therethrough which, when the shell casing *S* is held by the retaining member, is in vertical alignment with the primer cap aperture *p* in the back wall of the shell casing *S*. Thus, the retaining member *32* presents a vertical bore through the table portion *6* and this bore conforms in diameter substantially to the diameter of the primer cap aperture *p* in the shell casing.

Die member *D* receives in its internally threaded upper bore portion *a* a combined ejector and sizing member *59* and including an upper threaded body portion *60* engageable within the bore portion *a* and terminating at its upper end in the finger knob *n*. Depending from the threaded body portion *60* is an elongate stem portion *r* having adjacent its free end an enlarged sizing portion *64* and terminating at its free end in a reduced diameter nipple *61* which is adapted to be projected through the primer cap firing aperture, as shown, and punch out the spent primer cap *39a* from the spent cartridge shell casing. The punched out spent primer cap will, of course, fall downwardly through the aperture *32'* in the retaining member *32*. Associated with the threaded body portion *60* of the ejector means is a stop collar or lock nut member *58''* having a set screw, not shown, preferably associated therewith to retain the proper adjustment of the ejector means, as will be described.

The lowermost position of the carriage *9*, and consequently the lowermost position of the die means *D*, is shown in Fig. 3 and in this position the die means is adjusted vertically by threading the same within the ear portion *11* to achieve the proper height. At this point, the stop collar or lock nut *58* is threaded tightly against the ear *11* and held in place by its associated set screw *58'*. In this same position, the ejector means must be so positioned as to completely remove the spent primer cap *39a* from the primer cap aperture or pocket *p* in the shell casing *S*. For this purpose, the ejector means is adjusted vertically within the die body *D* so as to attain the proper height and, at this point, the associated stop nut *58''* is locked in place to retain the proper adjustment. The uppermost position of the carriage member is shown in Fig. 1 and it is noted in this respect that the

same is held normally in this position by cooperation between the detent member *69* and the pocket *70* in the side of the carriage member, as is shown. The lowermost position of the carriage member is normally retained by virtue of the engagement of the detent member *69* in the indentation or pocket *71*.

Rotatably supported in the bearing portions *20* of frame members *1* and *2* (Figs. 2 and 7) adjacent the upper end portions thereof is a transverse, horizontal shaft member *18* which has pinned thereto, as by the pin member *19*, a crank *16* having its forward free end portion pivotally secured, as by the pivot pin *17*, to a pair of depending link members *13* straddling the same and which straddle at their opposite ends and are pivotally secured, by means of pivot pin *14*, to an ear portion *15* formed at the upper end of the carriage base *10*. Thus, when the shaft *18* is rotated in opposite directions, the carriage *9* will slide vertically up and down in its guideways *12*, as previously described.

At least one end portion of the shaft *18* projects outwardly from a side of the frame *F* and a handle means *24* is associated therewith which may take the form as specifically shown in the drawings wherein the handle means consists of a bar projecting transversely through the free end portion of the shaft *18* and rigidly secured thereto as by set screw member *25*. To prevent longitudinal movement of the shaft *18*, an annular groove *23* is formed therein and into which the stem portion of a set screw member *21* carried by the frame *F* may be projected, as will be most clearly seen in Fig. 7. As the handle *24* is rotated downwardly in the direction of the arrow, Fig. 2, the carriage *9* will be moved vertically downwardly from its position as shown to the lowermost position, as shown in Fig. 3. As the die member moves downwardly to receive the shell or cartridge casing *S*, the neck portion *66* of the shell will be reduced in diameter by the bore portion *62* of the die member while simultaneously therewith the nipple *61* of the ejector means will punch out the spent primer cap *39a*. When the die member is again withdrawn by moving the carriage *9* vertically upwardly, the resizing portion *64* of the ejector means will pass upwardly through the then necked down portion *66* of the shell casing *S* and will re-expand the same to conform to the proper diameter for inserting a new bullet thereinto. Thus, upon one complete up and down motion of the carriage, the shell casing is ridded of its spent primer cap, while at the same time the neck *66* thereof is resized so as to subsequently received a new bullet therein.

The previously mentioned guide portion *7* below the table portion *6* is provided with a vertical bore therethrough which is in alignment with the bore *32'* in the retaining means *32* and reciprocable within this guide bore is a reload plunger *8* terminating at its upper end in a reduced diameter stem portion *8'* presenting at its upper free end a concave depression to receive a new primer cap therein. The lower end of the reload plunger *8* is threaded, as shown most clearly in Figs. 2 and 8, and a stop collar *36* is adjustably located thereon and maintained in proper place by means of a set screw *36'*, the purpose of the stop collar being to engage the undersurface of the guide portion *7* to limit the upward travel of the reload plunger so that in its uppermost position it will be effective to properly insert a new primer cap into the primer cap aperture *p* in the shell casing or cartridge casing *S*. The guide portion *7* is provided with a depending bifurcated leg portion *27* which straddles one end of a lever member *26* and is pivotally secured thereto by means of a pin *28* extending through both members. The leg *27* is provided with horizontal slots *28'* in its bifurcated portions within which the pivot pin *28* rides. The lower end of the reload plunger *8* is bifurcated, as is illustrated most clearly in Fig. 8, and the same straddles an intermediate portion of the lever *26* and is pinned thereto as by means of the pivot pin *37*. The opposite free end

of the lever 26 is pinned as by the member 30 to a clevis at the lower end of operating rod 29 which extends vertically therefrom and through a vertical bore in the post 31 which projects horizontally, rearwardly from the carriage base 10 through the slot 3' in the web 3 as is shown most clearly in Figs. 2 and 3.

The upper end of the operating rod 29 is threaded as shown and is provided thereon with lock nuts 29' to overlie the post 31. Thus, it will be seen that the handle 24 and its associated linkage connected to the carriage 9 forms a common operating means for the carriage and for the reload plunger 8 for performing sequential reloading operations in a manner to be described presently.

A transfer plate 41 is pivotally secured to the undersurface of the table portion 6 in face-to-face contact therewith, such connection being effected by means of a pivot bolt 43. The transfer plate includes a projecting ear portion 41', best shown in Fig. 5, and secured in spaced relation on the undersurface of the table portion 6 in depending relation thereto are a pair of stop pin members 55 and 56 which fix the extremities of the pivotal path of movement of the transfer plate. Projecting through a vertical bore in the table portion 6 is the reduced lower end portion 38', Fig. 6, of a magazine 38 and which includes a vertical sight slot 40 to determine whether or not there is a supply of primer caps 39 therein. The new primer caps 39 which are disposed within the magazine 38 are stacked therein and will normally tend to fall by gravity through the lower end thereof.

The transfer plate 41 is substantially equal in thickness to that of the individual primer caps 39 and said plate has an opening 45 therethrough which is normally closed at its bottom by an end portion 47 of a shutter or retainer 46, whereby the opening 45 will nest the caps 39 one at a time. When the transfer plate 41 is in the full line position as shown in Fig. 5, the opening 45 therein, see particularly Fig. 6, will be in alignment beneath the lower end of the magazine 38 and the lowermost primer cap 39 will be disposed within such aperture 45 and will be retained in place therein by means of the end 47 of the shutter or retainer 46 which is pivotally secured to the transfer plate by means of the pivot 48. The transfer plate carries a stop pin 50 and a spring 49 connected between posts on the retainer strip 46 and the transfer plate normally urges the retainer strip to a position with its end 47 underlying the aperture 45 in the transfer plate so as to form a pocket therewith for receiving the lowermost primer cap in the stack disposed within the magazine 38.

The upper portion of the stem 8' of the reload plunger 8, when the reload plunger is in its lowermost position, as shown in Figs. 3 and 13, is in the path of movement of the retainer end 47 when the transfer plate is swung to its reload position shown in dotted line in Fig. 5. Thus, when the transfer plate is swung to its dotted line position shown in Fig. 5, the stem 8' of the reload plunger will cause the retainer end 47 to swing aside and uncover the underside of the aperture 45 through the transfer plate and will deposit the primer cap in the depression in the upper end 8' of the reload plunger stem.

The table portion 6 slidably carries a detent member 51, best shown in Fig. 6, which is normally spring urged downwardly by the action of the spring leaf 53 secured to the table portion top by the screw 54, the detent being engageable within a depression 52 in the plate 41 when the latter is in the dotted line position shown in Fig. 5. It will be noted that the transfer plate includes the enlarged segmental portion 42 underlying the table portion 6 and of such an area as to cover the underside or lower end portion of the magazine 38 regardless of the position within which the transfer plate is disposed. The transfer plate also includes a horizontally projecting lever portion 44 whereby the transfer plate may be manipulated manually.

In operation, the empty shell casing S is placed in the retainer member 32 with the carriage 9 moved to its uppermost position as shown in full lines in Figs. 1 and 2. In the uppermost position of the carriage 9, the reload plunger 8 will also be in its uppermost position so that the upper end of the stem 8' of the reload plunger is almost, but not quite, entered into the primer cap aperture p in the shell casing S. Of course, at this time, the spent primer cap 39a is still in the shell casing S. With the parts in this position, the operating handle 24 is rotated downwardly to lower the carriage and cause the die D and its associated ejector means to move toward the shell casing S. At the same time, due to its weight, the reload plunger 8 will be lowered also, withdrawing the reload plunger stem 8' from the vertical bore 32' in the retainer member 32 so as to permit the spent primer cap to fall downwardly through the bore 32'. As the carriage is moved to its lowermost position, the die performs the necking down operation on the neck 66 of the shell casing 20 while, at the same time, the nipple 61 of the ejector means ejects the spent primer cap 39a. With the parts still in the lowermost position, the transfer plate 41 is manipulated by swinging its lever 44 in the direction of the arrow, Fig. 9, so that a new primer cap is transferred 25 from the magazine 38 to a position resting upon the upper end of the stem 8' of the reload plunger. The common operating means is then moved in the opposite direction to raise the carriage 9 and elevate the reload plunger 8 so that the new primer cap is pressed into the shell casing 30 S. At this point, the shell casing is removed and is ready for filling with powder.

A modified form of primer cap transfer mechanism is illustrated in Figs. 9 and 10 and it will be seen that in this modification the table portion 6' is provided on its undersurface with a T slot slidably receiving the transfer plate 141. The body 142 of the transfer plate carries a retainer strip 146 similar to that previously described and having associated therewith a spring means 149 to normally urge the same into closing relation with a vertical opening 145 through the transfer plate. A stop pin 150 is carried by the retainer plate 141 so that the spring 149 normally urges the retainer strip 146 to the proper underlying position to bore 145.

One corner of the transfer plate is provided with an offset ear portion 145' underlying an adjacent portion of the table 6' and engageable with a pair of stop pins 146' and 147' to limit the two extremities of travel of the transfer plate 141. In these two positions of the plate, the transfer plate opening 145 is respectively aligned with the lower end of the magazine 38 and the lower end of the bore 32' through the retainer means 32. As is the case in the previously described mechanism, the reload plunger stem 8' is in the path of movement of the retainer strip 146 so that the stem moves the retainer aside when the transfer plate is moved to the loading position shown in dotted lines in Fig. 9 to deposit a new primer cap on the upper end of the stem portion 8' for subsequent insertion of the new primer cap into the shell casing S.

When a desired quantity of shell casings have been provided with primer caps, they are then reinserted into the press, one at a time, for the purpose of affixing a new bullet thereto. For this purpose, the ejector means is removed from the die D and replaced by a bullet press mechanism 65 as shown in Fig. 11. The bullet press member is similar to the ejector means in some respects except that its threaded body portion terminates within the die proper above the bore portion 62 thereof and presents therat a conical bullet nose receiving depression 72', as most clearly shown in Fig. 11. Of course, a stop collar 72" is associated with the bullet press member to obtain the proper adjustment thereof. With the die in its uppermost position, a new bullet 65 is lightly pressed into the upper end of the neck 66 and then the die is lowered so

that the bullet engaging member 72 thereof will force the bullet into the neck 66. The bullet engaging member 72 is properly adjusted when the same engages the nose of the bullet 65 just as the upper end of the neck 66 of the shell casing S enters into the bore 62 of the die. The final size of the shell casing neck 66 as occasioned by the die portion 62 is correct for the finished product and, of course, at the same time that the bullet is being pressed into place, the neck 66 of the shell is being reduced slightly in diameter to firmly engage and clamp upon the bullet portion which is projected into the neck.

Fig. 12 shows a means for removing the bullet from a shell casing S should the occasion for such removal arise. This removing mechanism is associated with the previously mentioned die D and includes an externally tapered collet member 67 which has at least a major portion thereof of greater diameter than the bore portion b of the die. The collet 67 is provided with an upwardly projecting bar portion M threaded at its upper end and receiving thereon a wing nut 68 bearing against a washer 68' overlying the upper end of the die member D. When the bullet extractor is used, the carriage 9 is lowered so as to engage the tapered collet 67 onto the bullet 65 and continued downward pressure on the operating means will cause the collet to be forced into the bore portion b and due to the collet taper, the collet will firmly grip the bullet 65. At this point, the downward pressure is maintained on the operating means and the wing nut 68 is screwed up tight so as to retain the gripping action of the collet upon the bullet. The operating means is operated in the reverse direction to withdraw the bullet from the shell casing S.

Although certain specific embodiments of the invention have been shown and described, it is obvious that many modifications thereof are possible. The invention, therefore, is not to be restricted except insofar as is necessitated by the prior art and by the spirit of the appended claims.

What is claimed is:

1. A cartridge casing reconditioning apparatus comprising an upstanding frame, a horizontal table on said frame, said table having a cartridge casing seat on its upper surface and a vertical bore extending therethrough axially of said seat, a vertically movable support slidably mounted on said frame above said table, a die having a die socket corresponding to the outer shape and dimensions of a cartridge casing, a plunger carried by said die and disposed axially of said die socket with the free end thereof protruding through the open end of said socket and beyond the end of said die, an enlarged sizing portion on said plunger, means mounting said die on said support axially of said seat with said die positioned to fit down over a cartridge casing on said seat and said plunger penetrating the cartridge casing and punching the spent primer cap from the breach of the casing to be discharged through said seat bore, said table having an aperture therethrough spaced from said seat bore, a cap magazine mounted on top of said table axially of said aperture for delivering caps through said aperture by gravity, a carrier having an opening therethrough and a thickness corresponding to that of a cap, said carrier being mounted on the underside of said table for movement in face-to-face contact between positions in which said opening is respectively aligned with said aperture to receive one cap at a time from said magazine and with said bore to position the cap thereunder, a shutter movably mounted on

the underside of said carrier, means urging said shutter to normally underlie said opening and retain a cap therein but permitting movement of said shutter from under said opening, means for moving said carrier between said positions, a reload plunger slidably mounted on said frame beneath said table in axial alignment with said bore for lifting a cap in said opening up through said bore and pressing the cap into the cartridge casing breach on said seat, means for simultaneously reciprocating in the same direction said support and said reload plunger to lower said die to reshape a cartridge casing and punch the spent cap therefrom as said reload plunger is lowered to free said bore for discharging the spent cap and to lift said die to free the cartridge breach as said reload plunger is lifted to feed a new cap from said carrier up through said bore and press it into the cartridge breach, and means for positioning said reload plunger at the lower end of its stroke with the upper end of said plunger immediately below the path of said carrier but in the path of said shutter to remove said shutter from beneath said opening as said carrier is moved into alignment with said plunger and bore to free the fresh cap in said opening for reloading the cartridge casing by upward movement of said reload plunger.

2. A cartridge casing reconditioning apparatus comprising a horizontal table having a cartridge casing seat on its upper surface and a vertical bore extending therethrough axially of said seat, said table having an aperture therethrough spaced from said seat bore, a cap magazine mounted on top of said table axially of said aperture for delivering caps through said aperture by gravity, a carrier having an opening therethrough and a thickness corresponding to that of a cap, said carrier being mounted on the underside of said table for movement in face-to-face contact between positions in which said opening is respectively aligned with said aperture to receive one cap at a time from said magazine and with said bore to position the cap thereunder, a shutter movably mounted on the underside of said carrier, means urging said shutter to normally underlie said opening and retain a cap therein but permitting movement of said shutter from under said opening, means for moving said carrier between said positions, a reload plunger slidably mounted beneath said table in axial alignment with said bore for lifting a cap in said opening up through said bore and pressing the cap into the cartridge casing breach on said seat, means for reciprocating said reload plunger to lower said reload plunger to free said bore and to lift said reload plunger to feed a new cap from said carrier up through said bore and press it into the cartridge breach, and means for positioning said reload plunger at the lower end of its stroke with the upper end of said plunger immediately below the path of said carrier but in the path of said shutter to remove said shutter from beneath said opening as said carrier is moved into alignment with said plunger and bore to free the fresh cap in said opening for reloading the cartridge casing by upward movement of said reload plunger.
